No. 567

Samuel D. Vose, of Albany, N.Y.
Letters Patent No. 567 - Dated May 24th 1853.

To schedule referred to in these Letters Patent and making part of the same

To all whom it may concern: Be it known that I, Sam'l D. Vose, of the City and County of Albany, and State of New York, have invented or produced a new

Design for a Parlor Stove (D), and I do hereby declare that the following is a full and exact description of the same, reference being had to the drawings annexed, making part of this specification.

The invention not being easily described in words, reference is made to the drawings.

In the drawings the letter U refers to the urn of the stove

"	T	"	"	"	top	"	"	"
"	I	"	"	"	front	"	"	"
"	H	"	"	"	hearth	"	"	"
"	G	"	"	"	gratefender	"	"	"
"	AP	"	"	"	ash plate	"	"	"
"	B	"	"	"	blower	"	"	"

My invention has no reference to any single moulding or ornament on said plates, but consists in the configuration & disposition of the ornaments in connection with the mouldings.

I claim no separate configuration or part,

What I claim as my invention & desire to secure by letters Patent of the United States, is the combination of mouldings & ornaments as arranged in the Parlor Stove (D), the whole forming an ornamental design.
